UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed September 5, 1919. Serial No. 321,888.

To all whom it may concern:

Be it known that I, KENNETH S. JOHNSON, a citizen of the United States, residing at Jersey City, in the county of Hudson, 5 State of New Jersey, have invented certain new and useful Improvements in Signaling Systems, of which the following is a full, clear, concise, and exact description.

This invention relates to circuit arrangements for signaling systems wherein repeaters or amplifiers are employed.

As is well known in the art, considerable difficulty is encountered in repeater or amplifier circuits, particularly of the two-way type in preventing the amplifiers from howling or singing. This condition is due to the fact that part of the amplified energy in the output of the amplifier finds its way back into the input of the amplifier to be re-amplified thereby causing the amplifier to howl or sing. In accordance with this invention, it has been found that this condition may be overcome by associating with the line and the repeater an impedance and a transformer having a plurality of windings so designed that the repeater input circuit and output circuit are conjugate, thereby preventing this feedback of energy while still maintaining a high efficiency in the system.

It has been hitherto proposed to prevent this singing by connecting the repeaters between the telephone or signaling lines in a so-called four-wire circuit, two of the wires being employed to repeat in one direction, the other two being employed to repeat in the opposite direction. The arrangement provided in accordance with this invention requires only a three-wire circuit for two-way repeating between lines, and therefore from an economical standpoint has advantages over the four-wire circuit. It has also been found that the attenuation for signals is considerably reduced by the employment of a three-wire circuit, an important advantage in case the three-wire circuit is electrically long and is used as a trunk line to connect two central telephone stations for example.

As the line and the repeater may be associated with the transformer and the auxiliary impedance in a large number of ways to produce the desired result, this invention will be better understood by reference to the following detailed description taken in connection with the accompanying drawings

in which Fig. 1 represents this invention applied to a two-way repeating system in which one amplifier is employed for repeating in both directions. Fig. 2 illustrates this invention in connection with a two-way repeater system in which separate amplifiers are employed for repeating in opposite directions. Fig. 3 is a modification of Fig. 2. Fig. 4 illustrates how additional amplifiers may be inserted between the three-wire circuit and the two signaling lines, and Fig. 5 is a modification of Fig. 4.

In the two-way repeating system illustrated in Fig. 1, two telephone lines 7, 8 and 9, 10 are associated with each other by a three-wire repeater circuit comprising the three-line wires or branches 12, 13 and 14. The central branch 13 includes line 9, 10 and is connected to the common terminal of windings 15 and 16 of transformer 17. Branch 12 contains the output of the amplifier 20 and is connected to a terminal of winding 15. Branch 14 includes the input of the amplifier 20 and is connected to the winding 16 of transformer 17. Current for the amplifier 20 is supplied by a battery 24. Inductance 25, which is in series with battery 24 prevents any substantial amount of the signaling currents from passing through the battery.

In order to prevent any energy from the output of amplifier 20 from being fed back into the input side of the amplifier, windings 15 and 16 of the transformer should be so designed with respect to the rest of the circuit that the current through winding 15 induces a counter-electromotive force in winding 16, equal to the electromotive force impressed thereon due to its conductive connection. By such an arrangement none of the amplified energy will find its way back to the input of the amplifier to be reamplified and produce the undesirable effect known as howling. It has been found that the value of the inductance of these two windings to prevent this howling should

satisfy the following relation, $\frac{L}{N} = \frac{S}{M}$, where

L is the impedance of line 7, 8, looking in the direction of the subscriber's set; N, the impedance of branch 13, which includes line 9, 10; S, the self impedance of windings 23; and M, the mutual impedance between windings 15 and 16. For a complete explanation of the theory involved, reference

is made to the Campbell Patent No. 1,254,472 of January 22, 1918, wherein are considered substation circuits comprising a line, a transmitter, a receiver and an auxiliary impedance so designed that they are made anti-side tone.

The operation of the circuit of Fig. 1 may now be explained as follows. Signals originating from transmitter 30 will induce corresponding variations in the current flowing through coils 15 and 16 which are in series relation with the input of amplifier 20. These signaling variations will then be amplified by amplifier 20, and will be impressed between points 31 and 32 of the three-wire circuit, so that they will pass out on line 9, 10 and be received by receiver 33. However, none of the amplified signals from amplifier 20 will pass through branch 14 on account of the previously defined relation. Signals from line 7, 8 will therefore be amplified by amplifier 20 without producing any singing in the circuit. Similarly, signals originating in transmitter 35 will be impressed between points 31 and 32 and therefore on the branch 14 which includes the input of the amplifier. The amplified signals in branch 12 will be impressed by transformer 17 on line 7, 8 and will be received by receiver 36. The three-wire circuit above described, therefore repeats in either direction without any of the amplified energy being fed back into the input of the amplifier to produce singing.

In Fig. 2 the three-wire circuit connected between lines 40 and 41 is similar to that of Fig. 1, except that it contains two amplifiers, one amplifying signal originating in line 40 and the other amplifying signals originating in line 41. Lines 40 and 41 are associated with each other by a repeater circuit, comprising the three branches 43, 44 and 45. Branch 44 includes the line 40 and is connected to the common terminal of windings 47 and 48 of transformer 49. Connected to the secondary of the transformer 49 is an auxiliary impedance 50, the function of which will be described later. Branch 43 includes the output of amplifier 51 and is connected to a terminal of winding 47. Branch 45 includes the input of amplifier 52 and is connected to a terminal of winding 48. The output of amplifier 52 is associated with line 41 by means of transformer 54. One terminal of the input of amplifier 51 is connected to the common terminal of windings 55 and 56 of transformer 54. The other input terminal is connected to that terminal of impedance 57 which is electrically remote from winding 56.

In order to prevent any of the amplified energy in the output of amplifier 51 from being impressed on the input of amplifier 52, the associated apparatus should be so

designed that the product of the impedance 50 times the mutual impedance of windings 47 and 48 equals the product of the impedance of branch 44 times the self impedance of winding 53. Similarly in order to prevent any of the amplified energy from the output of amplifier 52 from being impressed on the input of amplifier 51, the product of the impedance of line 41 times the number of turns in winding 56 should equal the product of the impedance of element 57 times the number of turns in winding 55.

With the apparatus designed to meet these requirements, amplifier 51 will amplify signals originating in line 41 and will impress them on line 40 without any of the amplified energy finding its way to branch 45 of the three-wire circuit. Similarly signals originating in line 40 will be amplified by amplifier 52 and impressed on line 41 without allowing any of the amplified energy to flow through branch 43 which includes output of amplifier 51.

In Fig. 3, lines 60 and 61 are connected by a three-wire circuit comprising branches 62, 63 and 64. Branch 62 includes line 60 and is connected to a terminal of winding 66 of transformer 67. Branch 63 includes the input of amplifier 69 and is connected to the common terminal of windings 66 and 70. Branch 64 includes an auxiliary balancing impedance 71. The output of amplifier 69 is associated with line 61 by means of a transformer 72. Amplifier 73 has its output connected to the winding 74 of transformer 67. One terminal of the input of amplifier 73 is connected to the common terminal of windings 77, 78 of transformer 72. The other terminal of the input of amplifier 73 is connected to that terminal of balancing impedance 80 which is electrically remote from winding 78.

In order to prevent any of the amplified energy in the output of amplifier 69 from being impressed on the input of amplifier 73, the product of the impedance of line 61 times the number of turns in winding 78 equals the product of the impedance of element 80 times the number of turns in winding 77. Similarly none of the amplified energy from amplifier 73 will be impressed on the input of amplifier 69, if the product of the impedance between branches 62 and 63 looking in the direction of line 60 times the number of turns in winding 70 equals the product of the impedance between branches 63 and 64 looking in the direction of line 60 times the number of turns in winding 66.

In Fig. 4 the three-wire circuit between lines 83 and 84 comprises the three branches 85, 86 and 87. A two-way repeating apparatus is located between the three-wire circuit and each of the lines 83 and 84. Branch

85 includes windings 88, 89 of transformers 90, 91 respectively. Branch 86 includes at one end, the input of amplifier 92 and, at the other end, the output of amplifier 93. 5 Branch 87 includes windings 94 and 95. The output of amplifier 92 has one of its terminals connected to the common terminal of windings 95, 96 of transformer 97. The other terminal of the output of amplifier 92 10 is connected to that terminal of balancing impedance 98 which is electrically remote from winding 96. The input of amplifier 93 is connected to line 83 by transformer 99. The input of amplifier 100 is connected to 15 winding 101 of transformer 91. The output of amplifier 100 is connected to line 83 in a manner similar to the connection of the output of amplifier 92 to line 84. Amplifier 103 has its input connected to a winding of 20 transformer 97 and has its output connected to a winding of transformer 90.

The following relations must be maintained in order to prevent any of the amplifiers illustrated in Fig. 4 from singing:

25 (a) None of the amplified energy from amplifier 103 will get into the input of amplifier 92 if the product of the impedance between branches 85 and 86 looking in the direction of line 83 times the number of turns in winding 95 equals the product of the impedance between branches 86 and 87 looking in the direction of line 83 times the 30 number of turns in winding 88.

35 (b) None of the amplified energy from amplifier 100 will get into the input of amplifier 93, if the product of the impedance of line 83 times the number of turns in winding 82 equals the product of the impedance of 102 times the number of turns in winding 81.

40 (c) None of the output of amplifier 93 will get into the input of amplifier 100 if the product of the impedance between branches 85 and 86 looking in the direction of line 84 times the number of turns in winding 94 equals the product of the impedance between branches 86 and 87 looking in the direction of line 84 times the number of turns in the winding 89.

45 (d) The input of amplifier 103 will receive none of the amplified energy from the output of amplifier 92 if the product of the impedance of line 84 times the number of turns in winding 96 equals the product of the impedance of element 98 times the number of turns in winding 95.

50 However, it is not necessary that these four conditions be satisfied simultaneously in order to prevent howling in the system of Fig. 4, for there will be no howling or singing if either condition (a) or condition (b) and either condition (b) or (c) are fulfilled.

55 Signals originating in line 84 will be impressed by transformer 97 on amplifier 103. The amplified energy in the output of ampli-

fier 103 by transformers 90 and 91 will be impressed on the input of amplifier 100, but none of this amplified energy will pass through branch 86 which includes the input of amplifier 92. The amplified energy in the 70 output of amplifier 100 is impressed on the substation set connected to line 83 without any of the energy finding its way back into the input of amplifier 93. By circuits 75 readily traced, it will be seen that signals originating in line 83 will be successively amplified by amplifiers 93 and 92 and impressed on line 84 without causing any of the amplifiers in the circuit to sing.

In the modification illustrated in Fig. 5, 80 the three-wire circuit is shown to be subdivided in order to permit the insertion of additional amplifiers. One part of the three-wire circuit comprises branches 105, 106 and 107; the other part of the three-wire circuit comprises branches 108, 109 and 110. Branch 105 includes winding 111 of transformer 112, a terminal of the input of the amplifier 113, winding 114, a terminal of the output of amplifier 113 and winding 115 of 85 transformer 116. Branch 106 includes the input of amplifier 117, the battery 119 and the output of amplifier 120 and is connected between the common terminal of windings 111, 121 and the common terminal of windings 115 and 122. Branch 107 includes winding 121, a terminal of the input of the amplifier 113, winding 125, and winding 122. Coils 114 and 125 are of low resistance 90 and are so wound on a common core as to offer high impedance to currents which in transmission from the line 150 to line 139 would tend to flow in the outside wires 105 and 107 past the connections of said wires to repeater 113, but to offer negligible impedance to currents which in transmission from line 139 to line 150 flow over wires 105 and 107 in parallel for one side of the line. 95

100 Branch 108 includes windings 130 of transformer 116 and winding 131 of transformer 132. Branch 109 includes the input of amplifier 120 and the output of amplifier 135. Branch 110 includes winding 136 of transformer 116 and winding 137 of transformer 132. The input of amplifier 135 is 105 connected to the telephone line 139 by means of a transformer 138. Connected between windings 157, 158 and windings 159, 160 of the secondary of transformer 138 is an auxiliary impedance 141. The midpoints of windings 157, 158 and 159, 160 are connected 110 to the output of the amplifier 143. The input of amplifier 143 is connected to a winding of transformer 132. Amplifier 145 has its input connected to a winding of a transformer 146 and has its output connected to a winding of transformer 112. The output of amplifier 117 is connected to line 150 in a manner similar to the connection of the 115 output of amplifier 143 to line 139.

120

125

130

None of the amplifiers of the circuit arrangement of Fig. 5 will sing if the following relations are maintained:

- (a) In order to prevent any energy in the output of amplifier 117 being impressed on the input amplifier 145, the product of the impedance of line 150 times the number of turns in windings 152 and 153 should equal the product of the impedance of element 155 times the number of turns in windings 151 and 154.
- (b) None of the output of amplifier 145 will get in the input of amplifier 117 if the product of the impedance between branches 105 and 106 looking in the direction of line 139 times the number of turns in winding 121 equals the product of the impedance between branches 106 and 107 looking in the direction of line 139 times the number of turns in winding 111.
- (c) None of the output of amplifier 113 will get into the input of amplifier 120 if the product of the impedance between branches 108 and 109 looking in the direction of line 139 times the number of turns in winding 136 equals the product of the impedance between branches 109 and 110 looking in the direction of line 139 times the number of turns in winding 113.
- (d) None of the output of amplifier 120 will get into the input of amplifier 113 if the product of the impedance between the central branch 106 and the outside branch 105 looking in the direction of line 150 times the number of turns in winding 122 equals the product of the impedance between branch 106 and branch 107 looking in the direction of line 150 times the number of turns in winding 115.
- (e) None of the output of amplifier 143 will be impressed on the input of amplifier 135 if the product of the impedance of line 139 times the number of turns in windings 158 and 159 equals the product of the impedance of element 141 times the number of turns in windings 157 and 160.
- (f) None of the output of amplifier 135 will be impressed on the input of amplifier 143 if the product of the impedance between branches 108 and 109 looking in the direction of line 150 times the number of turns in winding 137 equals the product of the impedance between branches 109 and 110 looking in the direction of line 150 times the number of turns in winding 131.

The operation of the circuit arrangement of Fig. 5 may then be explained as follows. Signals originating in line 150 will be impressed on amplifier 145 by transformer 146. The amplified signals from amplifier 145 by means of transformer 112 will be impressed through amplifier 113 upon the input of amplifier 143 by means of the transformers 116 and 132. However none of the output from amplifiers 145 and 113 will pass

through branch 106. After being amplified by amplifier 143 the signals are impressed on the substation set which is connected to the line 139. By circuits readily traced it will be seen that signals originating in line 139 will be successively amplified by amplifiers 135, 120 and 117 before being impressed on line 150. In transmitting from line 150 to line 139 only the two outside branches are employed, while in transmitting in the opposite direction the two outside branches in parallel form one side of the line, the other side of which is formed by the central branch.

It is evident that the principles underlying the circuit arrangement of Fig. 5 may be applied in cases where it is desired to employ a larger or smaller number of amplifiers between two signaling lines.

The broad aspect of this invention has been covered in a separate application filed by me, Serial No. 321,889, filed September 5, 1919.

It is to be understood that this invention may be employed with amplifiers or repeaters of other types than the one shown specifically in the drawings above described.

It is also to be understood that this invention is not limited to the particular forms described above, but that it may be variously modified without departing in any wise from the spirit of this invention as defined in the appended claims.

What is claimed is:

1. In a signaling system, two substations, a line circuit therebetween comprising two outside branches and a central conducting branch, a line circuit comprising two branches between each of said substations and the respective ends of said first line circuit, means for impressing signals from one of said substations through one of said two-branch lines upon said three-branch line with the two outside branches acting in parallel, the signaling currents returning over the remaining third branch, means for impressing signals from the other of said substations through its associated two-branch line upon said three-branch line with said outside branches acting serially to the signaling currents, and means included in said three-branch line for amplifying the signals received from one of said substations.

2. In a two-way signaling system, two substations, a line circuit comprising two outside branches and a central branch, a two-branch line between each of said substations and one end of said first line circuit, connections whereby signals from one of said two-branch lines are impressed on said three-branch line with said outside branches acting in parallel, the signaling currents returning over the remaining third branch, connections whereby signals from said other two-branch line are impressed on said three-

- branch line with said outside branches acting serially, a repeater for impressing on one of said two-branch lines amplified signals from the other two-branch line, said 5 repeater having input terminals and output terminals associated with said three-branch line, and means for preventing a substantial amount of energy from said output terminals from being impressed on said 10 input terminals.
3. In a two-way signaling system, a line circuit comprising two outside branches and a central branch, a two-branch line circuit connected to said three-branch line at one 15 end thereof, a second two-branch line circuit connected to said three branch line circuit at the other end thereof, a repeater having its input terminals connected serially with said central branch and its 20 output terminals associated with one of said two-branch lines, a second repeater having its output terminals coupled to said outside branches in series and having its input terminals associated with said second two-branch 25 line, and means for preventing the output energy of one of said repeaters from being impressed on the input terminals of said other repeater, while permitting each of said repeaters to impress on one of said 30 two-branch lines amplified signals from the other two-branch line.
4. In a two-way signaling system, a line circuit comprising three branches, a source of signaling currents, means for impressing 35 currents from said source upon said line with two of said branches acting in parallel, the currents returning over the third branch, a second source of signaling currents, means for impressing currents from 40 said source upon said line with the two branches acting serially that are employed in parallel for currents from said first source, repeater input terminals and repeater output terminals associated with said 45 three-branch line, said input terminals being connected serially to one of said branches, said branches having such impedance values that substantially none of the energy from said output terminals is 50 impressed on said input terminals, regardless of the degree of amplification produced by the repeater.
5. In a two-way signaling system, a line circuit comprising three branches, a source 55 of signaling currents, means for impressing currents from said source upon said line with two of said branches acting in parallel, the currents returning over the third branch, a second source of signaling currents, means for impressing currents from said source upon said line with the two branches acting serially that are employed in parallel for currents from said first source, repeater input terminals and 60 repeater output terminals associated with 65 said circuit, said output terminals being connected serially to one of said branches, and means for preventing said input terminals from receiving any substantial amount of energy from said output terminals, regardless of the degree of amplification produced by said repeater. 70
6. In a two-way signaling system, two substations, a line circuit comprising two outside branches and a central branch, a two-branch line between each of said substations and one end of said first line circuit, an impedance element, said outside branches being serially connected at one end by said element, said central branch being connected at one end to an intermediate point of said element, repeater input terminals and repeater output terminals associated with said circuit, the impedance of said element and the impedance of said outside branches with respect to said central branch being such that none of the energy from said output terminals is impressed on said input terminals, regardless of the degree of amplification 80 produced by the repeater. 85
7. In a two-way signaling system, two substations, a line circuit comprising two outside branches and a central branch, an inductance, said outside branches being serially connected at one end by said inductance, said central branch being connected to an intermediate point of said inductance, a repeater having input terminals and output terminals so associated with said circuit that singing of said repeater is prevented regardless of the degree of amplification produced thereby, means for impressing signals from one of said substations on said central branch with said outside branches acting in parallel, and means for impressing signals from said other substation on said circuit with said outside branches acting serially. 90 95
8. In a signaling system, two substations, means for providing two-way repeating between said substations, said means comprising a three-branch line circuit, means for impressing signaling currents from one of said substations upon said line with two of the branches acting in parallel, the currents returning over the third branch, means for impressing currents from the other substation upon said line with the branches acting serially that act in parallel for currents of the other substation, and an amplifying repeater having input terminals and output terminals so arranged with said line circuit that singing of said repeater is prevented regardless of the degree of amplification produced thereby, one kind of said terminals being connected in one of said branches. 100 105 110
9. In a two-way signaling system, a three-branch line circuit, a substation asso- 115 120 125 130

- 6 ciated with said circuit at each end thereof, means for amplifying signals from one of said stations, a second means for amplifying signals from said other substation, connections whereby signals from one of said substations are impressed on said first amplifying means with two branches of said line circuit acting in parallel, and connections whereby signals from said other substation 10 are impressed on said second amplifying means with two of said branches acting serially said connections being such that singeing of said amplifying means is prevented regardless of the degree of amplification 15 produced thereby.
10. In a two-way signaling system, two substations, a line circuit therebetween comprising two outside branches and a central branch, said outside branches being employed in parallel for transmission in one direction between said substations, said outside branches being employed serially for transmission in the opposite direction, a repeater having its input terminals associated 20 with one of said branches for receiving signals from only one of said substations, a second repeater having its output terminals associated with another of said branches for impressing signals on the other of said 25 substations only, and means for preventing said input terminals from receiving any substantial amount of energy from said output terminals regardless of the degree of amplification produced by said repeater.
15. 11. In a two-way signaling system, a line circuit comprising two outside branches and a central branch, a source of signaling currents, means for impressing currents from said source upon said line with said two outside branches acting in parallel, the currents returning over said central branch, a second source of signaling currents, means for impressing currents from said second source upon said line with said two outside 40 branches acting serially, repeater input terminals included serially in said central branch, repeater output terminals coupled to said outside branches, said input terminals and said output terminals being conjugate for all degrees of amplification obtained from said output terminals.
12. In a two-way signaling system, two substations, a line circuit therebetween comprising two outside branches and a central branch, an impedance element, a second impedance element, said outside branches being serially connected at their ends by said impedance elements, said central branch being connected at its ends to intermediate 55 points of said elements, repeater input terminals included serially in one of said branches, repeater output terminals associated with the other two of said branches, said input terminals and said output terminals being conjugate.
13. In a two-way signaling system, two substations, a line circuit therebetween comprising two outside branches and a central conducting branch, an inductance element, a second inductance element, said outside 70 branches being connected serially at their ends by said elements, said central path being connected to intermediate points of said elements, an amplifier having its input terminals connected serially in said central path, a second amplifier having its output terminals coupled to one of said elements, means for impressing signals from one of said substations on said first amplifier, and means for impressing signals from said 75 other substation on said second amplifier.
14. In a two-way signaling system, two substations, a line circuit comprising two outside branches and a central conducting path, a two-branch line between one end of said circuit and one of said substations, a second two-branch line between the other end of said circuit and said second substation, an inductance, a second inductance, said outside branches being connected serially at their ends by said inductances, said central path being connected at its ends to intermediate points of said inductances, an amplifier having its output terminals inductively coupled to one of said inductances, a second amplifier having input terminals inductively connected to said second inductance, a third amplifier having its input terminals connected serially in said central 90 path, connections whereby signals from one of said two-branch lines are impressed successively on said first and said second amplifiers, and connections whereby signals from said other two-branch line are impressed on said third amplifier, said connections being such that said third amplifier receives substantially none of the amplified energy from said first two amplifiers.
15. In a two-way signaling system, a two branch line, a second two-branch line, a three-branch line between said other lines, an amplifier having its input terminals responsive to current flowing serially through two branches of said three-branch line, said amplifier having its output circuit terminals associated with said first two-branch line for impressing on said first two-branch line amplified signals from the second two-branch line, and a second amplifier having 105 its input terminals responsive to current flowing in parallel through the above mentioned two branches of said three-branch line, said second amplifier having its output circuit terminals associated with said second two-branch line for impressing on said last 110 mentioned line amplified signals from the first two-branch line.
16. In a signaling system, two substations, a line circuit comprising two outside branches and a central conducting path 115

stretching between points geographically remote, a line circuit comprising two branches between each of said substations and the respective ends of said first line circuit, means for impressing signals from one substation serially upon said two outside branches, means for impressing signaling currents from the other substation through its associated two-branch line upon said first line circuit with said two outside branches acting in parallel, the currents returning over

said central conducting path and an amplifier having input and output terminals for amplifying signals from one of said substations, said input and output terminals being so connected in said system that said terminals are conjugate regardless of the degree of amplification of said amplifier. 15

In witness whereof, I hereunto subscribe my name this 2nd day of September A. D., 20 1919.

KENNETH S. JOHNSON.
